UNITED STATES PATENT OFFICE.

HENRY T. DOULETT, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EYELETING MACHINE.

Application filed November 13, 1914. Serial No. 871,990.

To all whom it may concern:

Be it known that I, HENRY T. DOULETT, a citizen of the United States, residing at Brockton, in the county of Plymouth and 5 State of Massachusetts, have invented certain Improvements in Eyeletting Machines, of which the following description, in connection with the accompanying drawings, is a specification, like reference characters on 10 the drawings indicating like parts in the several figures.

This invention relates to machines for setting eyelets. The invention is herein set forth in its application to the clenching of 15 eyelets between two layers of an article of work, which operation in the manufacture of boots and shoes is known as blind eyeletting or invisible eyeletting. This application constitutes a continuation in part of my 20 copending application Serial No. 854,483, filed August 1, 1914.

An object of the invention is to provide improved mechanism by which the insertion of blind or invisible eyelets may be facilitated.

In accordance with a feature of the invention, the illustrated eyelet-setting tool has a clenching shoulder formed and arranged to pass through a lacing hole in one or more 30 layers of an article of work so as to clench an eyelet between two layers of the article. Said tool is provided with an abutment behind the eyelet-clenching or upsetting shoulder. In the illustrated embodiment of the 35 invention, the abutment behind the upsetting shoulder of the eyelet-clenching tool and the said upsetting shoulder are relatively adjustable lengthwise of the clenching tool. In the illustrated construction the 40 said abutment is also slidably mounted and spring-pressed toward the work to give it a considerable capacity for self-accommodation to different work thicknesses.

Also in the illustrated embodiment of the 45 invention there is a contracted or reduced portion immediately behind the upsetting shoulder of the eyelet-clenching tool. This construction renders the end of the eyelet barrel less likely to catch in the under surface 50 face of the upper layer during the setting operation.

The present invention is herein illustrated as embodied in a machine of the type shown,

for example, in United States Letters Patent No. 603,023, granted April 26, 1898 on application of Seymour Field, which machine is organized to provide for punching the eyelet-receiving holes by a tool separate from the eyelet-setting tool. It is to be understood, however, that the invention in 60 various of its aspects is not limited to embodiment in a machine of this type.

For a full understanding of the present invention reference is to be had to the following description and the accompanying 65 drawings, in which—

Figure 1 is a view in perspective showing a setting device embodying the invention and a punch as they are arranged in an eyeletting machine, together with a piece of 70 work being operated upon;

Figs. 2, 3 and 4 are enlarged views illustrating the operation of inserting and clenching an invisible eyelet; and

Fig. 5 is a vertical sectional view through 75 the setting device.

When the setting device is used in a machine of the type shown in said Field Patent 603,023, the lacing holes are punched by a separate punch provided for that purpose, 80 the setting device being utilized to feed the work from the punching locality to the eyelet-receiving locality as a step in each cycle of operations. It is unnecessary to illustrate the construction of the machine itself, 85 and for the sake of clearness it is omitted from the drawings. The machine is provided with a support for the work and with a punch which is operated preliminarily to the insertion of the eyelet to form the eyelet hole. As shown in Fig. 1 the punch K is located at the right hand side of the setting device A. When the punch has performed its function it is retracted so that the setting die may be moved to the right, inserted 90 in the hole and then moved to the left to feed work and register the hole with the lower die E.

The upsetting die consists in a curved upsetting shoulder 1 of such shape as to cause 100 the end of the eyelet barrel forced against it to be spread or flared outwardly, and is of such diameter that it may be passed through one or more layers so as to clench the eyelet between two of the layers. The 105 clenching position of the upsetting shoul-

der 1 is clearly shown in Fig. 2. Above the upsetting shoulder 1 the setting device is provided with a recess H or contracted portion of substantially less diameter than the 5 diameter of the upsetting shoulder. Consequently, when the setting device is inserted in the work, the upper layer will be momentarily stretched by the upsetting shoulder 1, and will then loosely surround the recess H. Above the recess H the setting device is provided with an elongated stem having an enlarged threaded portion 2 slotted at its upper end to receive a screw-driver. The portion 2 of the setting device is screwed 10 into a sleeve B which is made in such shape and size as to fit readily into the lever or other carrier of an eyeletting machine in place of the upsetting tool ordinarily used.

Surrounding the lower end of the sleeve 20 B and disposed with its lower end somewhat above the upsetting shoulder 1 of the setting device A is an adjustable sleeve or abutment C. This member is shaped at its lower end to bear upon the surface of the upper layer 25 of the work and to flatten the material and also the clenched end of the eyelet barrel; so that a very smooth appearance is imparted to the finished work. The member C is provided with a longitudinally extended slot 30 4 in one side, through which passes a screw 5 threaded into the sleeve B. A stiff compression spring 6 is interposed between the lower end of the sleeve 6 and an interior shoulder formed near the bottom of the 35 member C. The spring 6, therefore, normally holds the member C in its lowermost position, this position being determined by the engagement of the screw 5 with the upper end of the slot 4. The member C also 40 serves to limit the distance which the uppermost layer of the work can move up upon the tool, it being important to permit the upper layer of the work to move upwardly only so far as is necessary to insure the end 45 of the eyelet barrel being clenched entirely beneath it. As stated in my previous application, the member C may be clamped in any desired position, and the operation of the spring 6 eliminated if the requirements of 50 the work are better served by such arrangement of the parts. In any case, since the member C is used to determine the working relation of the shoulder 1 and the eyelet-receiving layers its position relatively to the 55 shoulder will be adjusted according to the thickness of the material through which the shoulder must pass to reach the desired working position.

Adjustment of the position of the setting 60 shoulder 1 and recess H with respect to the acting face of the member C may be effected by screwing the setting device A into or out of the sleeve B, the slot 3 being readily accessible for this purpose. As the work varies in the thickness of its layers, and also

in their number, it is important to have provisions for adjustment between the parts of the setting device, and on account of the adjustments herein disclosed, it has been found possible to produce a high grade of invisible 70 eyelet work in shoes of such varieties as are passed through a large factory in the regular course of manufacture.

Having thus described my invention, what is claimed as new is:

75

1. The combination of a punching and eyelet setting device for setting eyelets in one or more of the layers of a plurality of layers of material, comprising a punch and a setting device having a projecting setting 80 shoulder, a contracted portion above the setting shoulder; and an adjustable shoulder contiguous to said contracted portion:

2. A device for setting eyelets in one of a plurality of layers of a flexible material, 85 said device comprising a projecting setting shoulder; a contracted portion above the setting shoulder; and means constituting an adjustable shoulder contiguous to said contracted portion.

3. A device for setting eyelets in one of a plurality of layers of a flexible material, said device comprising an anvil and a co-operating setting device having a projecting setting-shoulder and a contracted portion 95 above the setting-shoulder.

4. An eyelet setting device consisting of means for setting eyelets in one of the outside layers of a plurality of layers of material, comprising a lower anvil, an eyelet positioning device and an upper setting device having a slightly projected setting-shoulder and a contracted portion above the setting-shoulder.

5. The combination of a punching and 105 eyelet setting device for setting eyelets in one or more of the layers of a plurality of layers of material, comprising a punch and a setting device having a projecting setting-shoulder and a contracted portion above the 110 setting-shoulder.

6. A machine for setting eyelets in one of two superposed layers of sheet material, having in combination, a punch for perforating the two layers while in engagement 115 with each other, an upsetting die constructed and arranged to be projected through the hole in one layer to bring its upsetting surface substantially into the plane of the inner surface of the other layer, and means for inserting an eyelet through the other layer and clenching its barrel against the upsetting die.

7. A machine for setting eyelets in one of two superposed layers of sheet material, having in combination, means for punching 125 both layers of material; an eyelet carrying setting die for inserting an eyelet in one layer; and an upsetting die of substantially the same diameter as the hole punched arranged to project through the other layer 130

and to clench the barrel of the eyelet upon the inner surface of the layer first mentioned.

8. A machine for setting eyelets in one of two superposed layers of sheet material, having in combination, means for simultaneously punching both layers of material, an upsetting die constructed and arranged to be projected through the hole punched in one layer until its upsetting surface is disposed substantially in the plane of the inner surface of said layer, and means for inserting an eyelet in the other layer and clenching its barrel against the upsetting die.
15. An eyelet-clenching tool having a clenching shoulder formed to pass through a lacing hole in one layer of an article of work so as to clench the eyelet between two layers, and an abutment behind said shoulder to engage the layer through which the clenching shoulder has passed.
20. In an eyeleting machine, a clenching tool having a clenching shoulder formed to pass through the lacing hole in one layer of an article of work so as to clench an eyelet between two layers, and means arranged to engage the first said layer to limit the distance which the said layer can move up upon the tool.
25. 11. In an eyeleting machine, a clenching tool having a clenching shoulder formed to pass through the lacing hole in one layer of an article of work so as to clench an eyelet between two layers, and a yielding abutment surrounding said tool behind but adjacent to said shoulder and arranged to engage the first said layer.
30. 12. In an eyeleting machine, a clenching tool having a clenching shoulder formed to pass through a lacing hole in one layer of an article of work so as to clench an eyelet between two layers, and an abutment surrounding said tool and arranged behind said shoulder to engage the first said layer, said abutment and said shoulder being relatively adjustable toward and from one another.
35. 13. An eyelet-setting device for setting eyelets in one of several layers of a shoe upper, having a curved upsetting shoulder extending outwardly from the body of the device at a substantial distance above the end thereof, said shoulder being constructed and arranged to spread the end of the eyelet barrel between the layers of the upper.
40. 14. A device for setting eyelets in one of a plurality of layers of a flexible material, comprising a setting device having a projecting setting shoulder, and adjustable means

above said setting shoulder for varying the distance between said setting shoulder and the under side of said adjustable means.

15. An eyelet-setting device consisting of means for setting eyelets in one or more of the layers of a plurality of layers of material, comprising an upsetting device having a slightly projecting outwardly and upwardly curved setting shoulder combined with an anvil cooperating therewith, said upsetting device being arranged to spread and progressively turn the end of the eyelet over on said material between the said layers.

16. In a machine for setting invisible eyelets in one or more of the layers of a plurality of layers of material, a die for inserting an eyelet through a hole punched in one or more of said layers, and an upsetting die having a shouldered projection forming a base portion and a reduced portion, the reduced portion being constructed and arranged, during the clenching operation, to extend into said last-named layer or layers, while the base portion extends through the other of said layers, said other of said layers being an outer layer, and an upsetting surface formed by the transverse surface of the shoulder between the base and the reduced portion.

17. A machine for inserting blind eyelets in one or more of the layers of a plurality of layers including an outer layer, having in combination, a reciprocatory eyelet carrying set, and a cooperating setting member having its end portion constructed and arranged to enter all said layers and a shoulder forming an upsetting surface sufficiently near the end to be carried substantially through said outer layer for clenching the eyelet barrel on the other layer or layers while a portion of the setting member remains in said outer layer.

18. A tool for use in eyeleting machines for setting blind eyelets in one of a pair of layers including an outer layer, having its end shaped to enter said layers and pass through both said layers thereof, and a shoulder forming an upsetting surface of relatively small diameter so located on the tool as to be carried substantially through said outer layer for clenching the eyelet barrel on the other of said layers independently of said outer layer.

In testimony whereof I have signed my name to this specification in the presence of two subscribing witnesses.
